UNITED STATES PATENT OFFICE.

JOHN J. RIDGWAY, OF BROOKLYN, NEW YORK.

DOOR CHECK AND LOCK.

SPECIFICATION forming part of Letters Patent No. 498,491, dated May 30, 1893.

Application filed November 21, 1892. Serial No. 452,641. (No model.)

To all whom it may concern:

Be it known that I, JOHN J. RIDGWAY, a citizen of the United States, residing at Brooklyn, in the county of Kings and State of New York, have invented an Improvement in Door Checks and Locks, of which the following is a specification.

My present invention is designed as an improvement upon the device described and illustrated in my application for Letters Patent, filed August 20, 1892, Serial No. 441,125. In my former device covered by said application a chain was employed to operate the door check and the same could not be operated with a key from without and the mechanism was somewhat complicated, and the devices were not adapted to the usual varieties of door trims or casings.

The object of my present invention is to adapt the parts to the trims or casing of doors, to reduce the noise incident to the operation of the mechanism, to close the door unobstructed and also to be able to employ a key inserted from the outside of the door to operate the mechanism, and also to so construct the mechanism that a chain will be unnecessary, and the parts will be in an advantageous place for being reached and grasped by the hand and operated, and placed in the several positions desired.

In carrying out my invention I employ a slotted plate pivoted to an attaching plate and one or more auxiliary plates which act in connection with the said attaching plate when the same is secured to the casing or trim of a door. The slotted plate is made with a rubber buffer, the object of which is to lessen the noise. Upon the door proper I provide a casing and attaching plate for a spring actuated T headed bolt and a second casing and attaching plate for a sliding spring actuated adjustable bar, the spring actuated bolt and spring actuated bar being connected by a rod. The casing containing the spring actuated bar has a mortise and the bar is provided with a finger button and a cross piece which work in the mortise to provide three positions for the mechanism which is adapted to be placed upon a door within easy reach of the hand, and I employ a key adapted to operate the sliding spring actuated bar and T headed

bolt so as to move said parts from outside the door, and also means for holding the bar down in its lowest position when desired.

In the drawings, Figure 1 is a perspective view illustrating my improvements. Fig. 2 is an elevation of the spring actuated bolt and casing, an elevation of the attaching plate and section of the slotted plate. Fig. 3 is an elevation, and Fig. 4 a vertical section of the spring actuated sliding bar and its casing. Fig. 5 is a plan, and Fig. 6 a vertical section of the slotted plate and door casing or trim, and Fig. 7 is a modification of the devices shown in Figs. 5 and 6. Fig. 8 is an elevation and section of an improved form of slotted plate. Fig. 9 is a plan of the same, and Fig. 10 is a cross section at the line x x of Fig. 8.

A represents the door, and B the molded casing or trim thereof. The plate a is slotted throughout the greater portion of its length and is provided with several notches 1 at its forward and outer end, and a rubber buffer 2 is secured to said plate by a screw 3 at the end of the slot in said plate.

a' represents the attaching plate, and there are lugs upon the face of said attaching plate and lugs a² on the slotted plate, and pins pass through these lugs in pivotally connecting the slotted plate and attaching plate, and the attaching plate is secured to the door trim by screws, as shown.

Auxiliary plates are shown at b and the same are provided with points b'. The object of these auxiliary plates is to fill up the gap which might otherwise exist between the back of the attaching plate and the main face of the trim against which the molded face is fastened, the upper part of the attaching plate being connected to the molding. These auxiliary plates b may be of any desired width, the width being governed by the width of the molding employed upon the trim. Two of these plates are employed one at either end of the attaching plate and the points b' and b² thereof enter respectively into the trim b and into small holes in the back of the attaching plate, these auxiliary plates being really distance plates so that the face of the attaching plate shall be vertical, and the lugs a² of the slotted plate are preferably made with cam ends, so that while the slotted plate can

be raised, it is prevented from falling below a horizontal position. The slotted plate *a*, the lugs *a*² and attaching plate *a'* of themselves are the same as are shown in my before 5 named application.

c represents a casing and *c'* an attaching plate connected therewith, the attaching plate being perforated for screws which secure the same upon the inner face of the door and adjacent to its upper corner. Within the casing *c* is the spring actuated bolt *d*. The opposite edges of said bolt are notched at 4, 5, near the end to form a **T** head. The office of this **T** head is to slide along through the slot 15 of the plate *a*, and I have shown by dotted lines in Fig. 6 the several positions of this bolt *d*. The position 13 is when the bolt is drawn down to its full extent and is below the slotted plate where it bears no relation 20 operatively to said plate. The position 14 is where the **T** head of the bolt comes above the plate *a* and in which position the bolt freely slides back and forth in the slot of said plate. The position 15 is where the bolt is fully elevated, its main portion rising within any one 25 of the three notches 1. This position is illustrated in Figs. 2 and 6. In this position the door would be secured or locked in its relation to the plate.

d' is the bolt stem connected to the bolt *d* and passing downward from said bolt over the face of the door.

e represents a casing, and *e'* an attaching plate connected therewith and provided with screw holes for screws by which it is attached to the face of the door at a convenient height for the hand.

f represents a spring actuated sliding bar movable vertically through the casing *e*, and 40 there is a back plate *f'* behind the bar *f* and a blade spring 8 between the plate *f'* and the back case of *e*; this spring forces the plate *f'* and bar *f* forward toward the front of the casing. The face of the casing *e* is mortised 45 at 6 and provided with notches 7 at opposite sides of the mortise, and the sliding bar *f* is provided with a wedge-shaped notch 9, a cross piece 11 and a finger button 10, the cross piece 11 being adapted to fit within the notches 7 50 of the mortise in the position shown in Figs. 3 and 4; and I provide a hook 12 pivotally connected to the lower end of the bar *f* whose office is hereinafter described, and *g* represents a key with a single bar *g'*, see Figs. 3 and 4.

55 The operation of the parts is as follows: In the position shown in Fig. 1 the spring actuated bolt *d* is withdrawn into the casing *c*; the spring actuated sliding bar *f* is drawn down in the casing *e* with the hook 12 projected and caught against the lower edge of the casing. In this position the door A can be opened and shut freely without any reference to the slotted plate *a*, and the same can be locked or unlocked with a mortise lock of usual character. If it is desired to leave a room or apartment so that it cannot be en-

tered, but yet so that ventilation may be obtained, the hook 12 is uncaught when the door is open and the finger button 10 grasped and the bar *f* brought into an intermediate position such as is shown in Figs. 3 and 4, where the cross piece 11 is projected by the spring 8 into the notches 7. In this position the upper end of the spring actuated bolt *d* is in the position 14, Fig. 6. As the person leaves the apartment and closes the door, the **T** head of the bolt *d* raises the slotted plate as the door shuts, and said **T** head falls in behind the slot of said plate and within the opening of the attaching plate between the auxiliary plates *b*. If now the door is opened the notched upper end of the bolt *d* moves through the slot of the plate *a* until it strikes the rubber buffer, 2, at which place the door will be securely held and cannot be farther opened 85 without breaking the parts. In this position the door can be moved back and forth in the short range obtained between a shut position and the slightly open position against the buffer 2. With the parts in this position if 90 a person desires to enter a room, he shuts the door, applies the key *g* from the outside and turns the bar *g'* against the wedge-shaped notch 9; the action of this is to push the bar *f* backward, press the spring 8, withdraw the cross piece 11 from the notches 7 and then the end of the bar *g'* will bear against the edge of the cross piece 11 and push the bolt bar *f* down into the casing and simultaneously withdraw the bolt *d* into the 95 position shown in Fig. 1, when the door can be opened. If it is desired to lock the door from the inside, the finger button 10 is grasped and the parts are brought into the position shown in Figs. 3 and 4, when the door is shut 105 with the bolt *d* raised to an intermediate position. The door is then opened, the head of the bolt *d* moving through the slot of the plate *a*, and when one of the three intermediate notched places 1 is reached the finger button 10 is pressed inwardly and raised; this elevates the bolt *d* within one of the notched places 1 into the position 15 of Fig. 6, wherein the door is substantially locked, that is to say, the spring actuated sliding bar 110 *f* is at its highest point in the casing *e* where the bar *g'* of the key cannot be brought to operate upon the wedge-shaped notch 9. In this position a door can be left slightly open 115 all day or all night and ventilation obtained for an apartment with little or no liability of a person being able to enter.

In some cases it may be desirable to operate the mechanism herein described solely from the outside of the door, as in sanitariums, hospitals, &c.; in this case the finger button 10 is removed or left off and the key alone is employed to operate the mechanism.

In Fig. 7 I have shown a modification of the slotted plate wherein the pivot of the 130 plate is put nearer the top of the attaching plate so as to bring the back stopping edge

16 of the slotted plate nearer to the attaching plate, so that there is less movement for the bolt d between the back edge 16 and the face of the door trim or casing b , but the device shown in Figs. 8, 9 and 10 which is intended to accomplish the same result is preferred by me, and the same is adapted for use with the buffer 2 and auxiliary plate b and the other devices herein set forth.

10 In the construction shown in Figs. 8, 9 and 10, the attaching plate a'' is provided with slotted lugs i k l in pairs and an open center. The pairs of lugs i and k are on the same level at each side of the open center and the pair of lugs l are central of the plate a'' and above the open center. The ends of the slotted plate a^2 adjacent to the attaching plate a'' are provided with lugs 20, 21 and pins 22 which pass through the lugs 20 and into the slots of the pairs of lugs i k and which move freely up and down therein. I provide an arm m pivoted at one end at 18 to the outer end of the slotted plate a^2 and the other end of this arm passes between the 25 pair of lugs l and is provided with a pin 23 adapted to move in the slots of said lugs l . This slotted plate a^2 is in this manner suspended horizontally by the plate a'' as shown by full lines, Fig. 8. Should it be desired to 30 shut the door A and simultaneously lock or secure it, the bolt d is left in either the position 14 or 15. As the door shuts the bolt d strikes the end of the plate a^2 raising it into the dotted position Fig. 8, wherein the pin 23 moves 35 up in the slots of the lugs l . As the door closes the back of the plate a^2 is raised with its lugs 20, 21, its pins 22 moving upward in the slots of the lugs i , k and the outer end of this plate falls. As the bolt d passes under 40 the plate a'' and in between the auxiliary plates b , the back of the slotted plate a^2 drops of its own weight and its back edges confine the bolt d if in the position 15 and lock the door, and if in the position 14 the extent to 45 which the door can be opened is limited by the slot of the plate a^2 through which the head of the bolt d moves until it strikes the buffer 2, as heretofore set forth.

When the door is shut from within it can 50 also be substantially locked by projecting the bolt d to the highest position 15, the bolt then coming behind the attaching plate and between the auxiliary plates b , its stopping edge being the point 16 in Figs. 6, 7 and 8, the construction Figs. 7 and 8 being more advantageous for this feature of the bolt than the construction Fig. 6 because there is less motion possible to the door.

55 A modification of the auxiliary plates b is shown in Fig. 1, where the points b^2 are dispensed with and the forward edges of the plates are elevated and provided with holes for the attaching screws which pass through the plate a' , these attaching screws in this instance doing double duty.

60 My improvements are in no manner con-

nected with ordinary mortise locks for doors nor do they detract from the use of such locks in securing a door in the well known and usual manner.

70 I claim as my invention—

1. The combination in a door check and lock with a spring actuated bolt having a T head and means for retaining the same in its various positions, of an attaching plate adapted to be connected to a door casing, a slotted plate pivoted thereto and engaged by the T head of the bolt, and a rubber buffer 75 secured near the outer end of the slotted plate and against which the T head of the bolt stops, substantially as set forth.

2. In a door check and lock, the combination with a slotted plate, of an attaching plate pivoted to the slotted plate, one or more auxiliary plates at right angles to the attaching 85 plate and adapted to maintain the attaching plate in a vertical position, the auxiliary plates being provided with means for engaging the attaching plate and trim of a door, substantially as set forth.

90 3. The combination in a door check and lock with a bolt, of an attaching plate adapted to be connected to the door casing, a slotted plate occupying a nearly horizontal position, and devices by which said slotted plate is connected to the attaching plate so that the same can be lifted vertically by said bolt as it passes along beneath it, substantially as specified.

4. The combination in a door check and lock with a bolt, of the attaching plate a'' having slotted lugs i , k , l , and an open center, of the slotted plate a^2 having lugs and pins engaging the lugs i and k , the arm m pivoted to the outer end of the plate a^2 and having a 105 pin 23 engaging the lugs l , substantially as and for the purposes set forth.

5. The combination with the slotted plate and the attaching plate to which the same is pivoted, of a spring actuated bolt having a 110 T head, a spring actuated sliding bar and a bolt stem connecting the same, casings for said bolt and bar and means, substantially as specified, connected to the sliding bar whereby various positions of the same and the 115 spring actuated bolt may be maintained, substantially as set forth.

6. The combination with the slotted plate and the attaching plate to which the same is pivoted, of a spring actuated bolt, a spring 120 actuated sliding bar connected therewith, casings for said bolt and bar, a catch for holding the parts down, a projection or cross piece on the sliding bar for holding the parts at an intermediate position, and a finger piece for 125 operating the parts to attain the several positions, substantially as set forth.

7. The combination with the slotted plate a , the attaching plate a' to which the same is pivoted, of the spring actuated bolt d and its 130 casing and the stem d' , the sliding bar f and its casing e , a spring 8 for actuating the same

and pressing it forward in the case, said bar *f* being provided with a wedge-shaped notch 9 and a key with a single bar *g*' for operating the parts, substantially as set forth.

5 8. In a door check and lock, the combination with a slotted plate, an attaching plate pivoted thereto, a spring actuated bolt engaging the slotted plate and a bolt stem or connection *d*', of the casing *e* and its attaching plate *e*', the face of the casing being mortised at 6 and provided with notches 7, the sliding bar *f* within the casing having a wedge-shaped notch 9, a cross piece 11 and a spring 8 for pressing the same forward in the 15 casing, and a key *g* with a bar *g*' acting against the wedge-shaped notch 9 in operating the parts, substantially as set forth.

9. In a door check and lock, the combination with the slotted plate *a*, the attaching plate *a*' pivoted thereto, a spring actuated bolt *d* and 20 bolt stem *d*', of the casing *e* and its attaching plate, said casing having a face mortise 6 with side notches 7, the sliding bolt *f* within the casing, the back plate *f*', the spring 8 for pressing the sliding bar forward in the casing, a cross piece 11 upon the sliding bar, a finger button 10 and hook 12, substantially as and for the purposes set forth.

Signed by me this 12th day of November, A. D. 1892.

JNO. J. RIDGWAY.
